UNITED STATES PATENT OFFICE.

EARLE W. GOODNOW, OF LANSING, MICHIGAN, ASSIGNOR TO THE "NEW-WAY" MOTOR COMPANY, OF LANSING, MICHIGAN.

COOLING DEVICE FOR INTERNAL-COMBUSTION ENGINES.

1,247,819.

Specification of Letters Patent. Patented Nov. 27, 1917.

Application filed January 29, 1917. Serial No. 145,324.

To all whom it may concern:

Be it known that I, EARLE W. GOODNOW, a citizen of the United States, residing at Lansing, county of Ingham, State of Michigan, have invented certain new and useful Improvements in Cooling Devices for Internal-Combustion Engines, of which the following is a specification.

This invention relates to improvements in cooling devices for internal combustion engines.

Considerable difficulty has been experienced in the cooling of internal combustion engines employed on agricultural machines, such as grain harvesters, owing to the difficulty in properly installing the water cooled engines and the weight thereof and various other objections incident thereto and owing to the clogging and consequent inefficiency of air cooled engines heretofore employed in that relation.

The main object of this invention is to provide in an internal combustion engine an improved cooling means which is efficient and not likely to become clogged in use.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

Figure I is a front elevation of an engine embodying the features of my invention, the base being indicated by dotted lines and certain other parts being shown conventionally.

Fig. II is a right hand elevation.

Fig. III is a detail view, partially in vertical section, on a line corresponding to line 3-3 of Fig. II.

Fig. IV is a detail vertical section on a line corresponding to the broken line 4-4 of Fig. I.

Fig. V is an enlarged detail section on a line corresponding to line 5-5 of Fig. II, showing the arrangement of the starting crank or hand piece.

In the drawing similar reference characters refer to similar parts throughout the several views, and the sectional views are

taken looking in the direction of the little arrows at the ends of the section lines.

Referring to the drawing, the cylinder 1 is provided with circumferential heat radiating flanges 2 connected by spaced connecting bars or rods 3. These flanges are common to the valve chamber 4, which is formed integrally with the cylinder,—see Fig. III. The cylinder 1 is mounted upon the top section 5 of the crank case, which is hinged to the bottom section 6 at 7,—see the dotted lines in Fig. IV, so that when the bolts 8 are removed the top section of the crank case and the parts mounted thereon may be tilted to facilitate the removal of the crank shaft 9, adjustment of the bearings, etc.

The bearings 10 are formed in sections, the sections being mounted on the top and bottom sections of the crank case. This arrangement of the crank case is substantially that shown in the Way Patent No. 870,001, Nov. 5, 1907. The fly-wheel 11 is provided with a web 12 having an inwardly projecting annular flange 13 on its inner side.

The valve actuating mechanism, designated generally by the numeral 14, is disposed between the fly-wheel and the crank case. The control mechanism, designated generally by the numeral 15 is also disposed between the fly-wheel and the crank case. This control mechanism comprises governor weights 16 mounted upon the hub 17 on the inner side of the fly-wheel. The valve actuating and controlling mechanisms are not described herein in detail, as such details form no part of my present invention.

The cylinder is provided with a casing 18 which is open on the side opposite the fly-wheel. On the flange 13 of the fly-wheel I mount a fan 19, the fan being arranged to 95 embrace the governor parts mounted upon the fly-wheel. The fan casing comprises a top section 21 and bottom section 22. The bottom section telescopes with the top section and is secured thereto by the screws 23. 100 The fan casing is divided along the line of the crank case so that the top section may be tilted with the top section of the crank case. The fan casing is open on its sides and is mounted so that its outer edge 24 is disposed between the fan and the fly-wheel, and embraces the flange 13 on the fly-wheel,—see Fig. III, the fan of the fly-wheel constituting an outer wall for the fan casing. The upper section of the fan casing 110

is built as a part of the cylinder casing 18, that is, it is permanently joined thereto, the joints, however, not being shown. The fan casing is connected to the cylinder case by a 5 throat having curved walls at 25 and 26 so that the air discharged from the fan is not obstructed in its passage to the cylinder and there are no places for material, such as chaff and the like to collect and clog the fan or 10 the other parts.

The top 27 of the cylinder casing is hinged at 28 so that it may be swung back or opened to provide access to the interior of the casing.

15 With the parts thus arranged, I provide a structure which is very efficient in cooling and also one which does not become clogged, even when embodied in engines employed upon harvesting machines and the like in 20 which the air is usually charged with dust, chaff, small bits of straw and the like.

The parts are so arranged that the structure is very compact and the engine may be conveniently mounted for use upon 25 machines, such as grain harvesters.

The starting crank or handle 29 is pivoted at 30 within a recess 31 on the side of the fly-wheel, the handle being adapted to swing down into the recess, as shown in Figs. II 30 and V, when not in use.

I have illustrated and described my improvements in a very simple and practical embodiment in which I have developed the same for the market. I have not attempted 35 to illustrate or describe certain modifications or adaptations in structural details which might be desirable for other adaptations, as I believe the disclosure made will enable those skilled in the art to which my invention relates to embody or adapt the same as 40 may be desired.

Having thus described my invention, what I claim as new and desire to secure by Letters Patent, is:

45 1. In a structure of the class described, the combination of a crank case comprising a base section and a cap section hinged upon the base section, a cylinder mounted on said cap section and provided with spaced circumferential heat radiating flanges, a crank 50 shaft the removal of which is facilitated by the opening of said crank case on its hinge, a fly-wheel provided with a web having an annual flange on its inner side, a valve and 55 control mechanism disposed between said engine body and fly-wheel and including governor parts mounted on said fly-wheel, a fan mounted on the flange of said fly-wheel to embrace the governor parts mounted 60 thereon, a cylinder casing open on the side opposite said fly-wheel, the top of said cylinder casing being hinged, a fan casing open at its sides disposed between said valve mechanism and fly-wheel with the edges of 65 its outer wall between the fan and fly-wheel

and surrounding said flange thereof, said fly-wheel constituting an outer wall for said fan casing, said fan casing comprising a top section mounted to swing with the top section of said crank casing and connected to the cylinder casing by a throat having curved walls, and a bottom section telescoping with and detachably secured to the top section, and a supporting bracket for said bottom section mounted on said crank case 75 base section.

2. In a structure of the class described, the combination of a crank case comprising a base section and a cap section hinged upon the base section, a cylinder mounted on said cap section and provided with spaced circumferential heat radiating flanges, a crank shaft the removal of which is facilitated by the opening of said crank case on its hinge, a fly-wheel provided with a web having an 80 annular flange on its inner side, a valve and control mechanism disposed between said engine body and fly-wheel and including governor parts mounted on said fly-wheel, a fan mounted on the flange of said fly-wheel, to embrace the governor parts mounted thereon, a cylinder casing open on the side opposite said fly-wheel, the top of said cylinder casing being hinged, a fan casing 85 open at its sides disposed between said valve mechanism and fly-wheel with the edges of its outer wall between the fan and fly-wheel and surrounding said flange thereof, said fly-wheel constituting an outer wall for said fan casing, said fan casing comprising a top section mounted to swing with the top section of said crank casing and connected to the cylinder casing by a throat having curved walls, and a bottom section detachably secured to the top section. 95

3. In a structure of the class described, the combination of a crank case comprising a base section and a cap section hinged upon the base section, a cylinder mounted on said cap section and provided with spaced circumferential heat radiating flanges, a crank shaft the removal of which is facilitated by the opening of said crank case on its hinge, a fly-wheel provided with a web having an 100 annular flange on its inner side, a fan mounted on the flange of said fly-wheel, a cylinder casing open on the side opposite said fly-wheel, the top of said cylinder casing being hinged, a fan casing open at its edges disposed with the edges of its outer wall between the fan and fly-wheel and surrounding said flange thereof, said fly-wheel constituting an outer wall for said fan casing, said fan casing comprising a top section mounted to swing with the top section of 105 said crank casing and connected to the cylinder casing by a throat having curved walls, and a bottom section telescoping with and detachably secured to the top section, and a supporting bracket for said bottom 110 section.

4. In a structure of the class described, the combination of a crank case comprising a base section and a cap section hinged upon the base section, a cylinder mounted on said cap section and provided with spaced circumferential heat radiating flanges, a crank shaft the removal of which is facilitated by the opening of said crank case on its hinge, a fly-wheel provided with a web having an 115 annular flange on its inner side, a fan mounted on the flange of said fly-wheel, a cylinder casing open on the side opposite said fly-wheel, the top of said cylinder casing being hinged, a fan casing open at its edges disposed with the edges of its outer wall between the fan and fly-wheel and surrounding said flange thereof, said fly-wheel constituting an outer wall for said fan casing, said fan casing comprising a top section mounted to swing with the top section of 120 said crank casing and connected to the cylinder casing by a throat having curved walls, and a bottom section telescoping with and detachably secured to the top section, and a supporting bracket for said bottom 125 section.

5. In a structure of the class described, the combination of a crank case comprising a base section and a cap section hinged upon the base section, a cylinder mounted on said cap section and provided with spaced circumferential heat radiating flanges, a crank shaft the removal of which is facilitated by the opening of said crank case on its hinge, a fly-wheel provided with a web having an 130 annular flange on its inner side, a fan mounted on the flange of said fly-wheel, a cylinder casing open on the side opposite said fly-wheel, the top of said cylinder casing being hinged, a fan casing open at its edges disposed with the edges of its outer wall between the fan and fly-wheel

section mounted on said crank case base section.

4. In a structure of the class described, the combination of a crank case comprising a base section and a cap section hinged upon the base section, a cylinder mounted on said cap section and provided with spaced circumferential heat radiating flanges, a crank shaft the removal of which is facilitated by the opening of said crank case on its hinge, a fly-wheel provided with a web having an annular flange on its inner side, a fan mounted on the flange of said fly-wheel, a cylinder casing open on the side opposite said fly-wheel, the top of said cylinder casing being hinged, and a fan casing open at its sides disposed with the edges of its outer wall between the fan and fly-wheel and surrounding said flange thereof, said fly-wheel constituting an outer wall for said casing.

5. In a structure of the class described, the combination of a crank case comprising a base section and a cap section hinged upon the base section, a cylinder mounted on said cap section, a crank shaft, the removal of which is facilitated by the opening of said crank case on its hinge, a fly-wheel, a valve and control mechanism disposed between said engine body and fly-wheel and including governor parts mounted on said fly-wheel, a fan mounted on said fly-wheel to embrace the governor parts mounted thereon, a cylinder casing open on the side opposite said fly-wheel, and a fan casing open at its sides disposed between said valve mechanism and fly-wheel and connected to deliver to said cylinder casing, said fan casing comprising a top section adapted to swing with the top section of said crank casing.

6. In a structure of the class described, the combination of a crank case comprising a base section and a cap section hinged upon the base section, a cylinder mounted on said cap section, a crank shaft, the removal of which is facilitated by the opening of said crank case on its hinge, a fly-wheel, a fan mounted on said fly-wheel, a cylinder casing open on the side opposite said fly-wheel, and a fan casing open at its sides disposed between said valve mechanism and fly-wheel and connected to deliver to said cylinder casing, said fan casing comprising a top section adapted to swing with the top section of said crank casing.

7. In a structure of the class described, the combination of a cylinder provided with spaced circumferential heat radiating flanges, a crank shaft, a fly-wheel provided with a web having an annular flange on its

inner side, a valve and control mechanism disposed between said engine body and fly-wheel and including governor parts mounted on said fly-wheel, a fan mounted on the flange of said fly-wheel to embrace the governor parts mounted thereon, a cylinder casing open on the side opposite said fly-wheel, the top of said cylinder casing being hinged, and a fan casing open at its sides disposed between said valve mechanism and fly-wheel with the edges of its outer wall between the fan and fly-wheel and surrounding said flange thereof, said fan casing being connected to the cylinder casing by a throat having curved walls, said fly-wheel constituting an outer side wall for said casing.

8. In a structure of the class described, the combination of a cylinder provided with spaced circumferential heat radiating flanges, a crank shaft, a fly-wheel provided with a web having an annular flange on its inner side, a fan mounted on the flange of said fly-wheel, a cylinder casing open on the side opposite said fly-wheel, the top of said cylinder casing being hinged, and a fan casing open at its sides disposed with the edges of its outer wall between the fan and fly-wheel and surrounding said flange thereof, said fan casing being connected to the cylinder casing by a throat having curved walls, said fly-wheel constituting an outer side wall for said casing.

9. In a structure of the class described, the combination of a cylinder, a crank shaft, a fly-wheel provided with a web having an annular flange on its inner side, a valve and control mechanism disposed between said engine body and fly-wheel and including governor parts mounted on said fly-wheel, a fan mounted on the flange of said fly-wheel to embrace the governor parts mounted thereon, a cylinder casing open on the side opposite said fly-wheel, and a fan casing open at its sides disposed between said valve mechanism and fly-wheel with the edges of its outer wall between the fan and fly-wheel and surrounding said flange thereof, said fly-wheel constituting an outer side wall for said casing.

10. In a structure of the class described, the combination of a cylinder, a crank shaft, a fly-wheel provided with a web having an annular flange on its inner side, a fan mounted on the flange of said fly-wheel, a cylinder casing open on the side opposite said fly-wheel, and a fan casing open at its sides disposed with the edges of its outer wall between the fan and fly-wheel and surrounding said flange thereof, said fly-wheel constituting an outer side wall for said casing.

11. In a structure of the class described, the combination of a cylinder, a crank shaft, a fly-wheel, a valve and control mechanism

disposed between said engine body and fly-wheel and including governor parts mounted on said fly-wheel, a fan mounted on said fly-wheel to embrace the governor parts 5 mounted thereon, a cylinder casing, and a fan casing disposed between said valve mechanism and fly-wheel.

In witness whereof, I have hereunto set my hand and seal in the presence of two witnesses.
